UNITED STATES PATENT OFFICE.

HENRY W. SCHULZE, OF MILWAUKEE, WISCONSIN.

GAS-PLATE.

966,480.

Specification of Letters Patent. Patented Aug. 9, 1910.

Application filed June 16, 1909. Serial No. 502,404.

To all whom it may concern:

Be it known that I, HENRY W. SCHULZE, residing in Milwaukee, in the county of Milwaukee and State of Wisconsin, have invented new and useful Improvements in Gas-Plates, of which the following is a description, reference being had to the accompanying drawings, which are a part of this specification.

This invention relates to improvements in gas plates for household or other uses and is adapted to rest on a suitable support, and to be used for cooking or heating purposes.

One of the objects of this invention is to provide a simple inexpensive burner plate which is adapted to be connected to a gas pipe and to use the gas therefrom as the heating medium.

A further object of the invention is to provide a gas plate in which the number of burner openings open at one time may be simply controlled in order to increase or diminish the area of the flame.

A further object of this invention is to provide a gas plate in which the valve controlling the gas supply is also adapted to control the number of burner openings in use so that a proper supply of gas is provided for each adjustment of the area of the burner in use.

With the above and other objects in view the invention consists of the gas plate and its parts and combinations, and all equivalents thereof.

In the accompanying drawing in which the same reference characters indicate the same parts in all of the views: Figure 1 is a vertical longitudinal sectional view of the complete gas plate shown connected to a gas pipe; Fig. 2 is a plan view thereof a part of the plate broken away to show interior construction; Fig. 3 is a transverse section of a fragment of the plate taken on line 3-3 of Fig. 1; Fig. 4 is a similar view taken on line 4-4 of Fig. 1; Fig. 5 is a similar view taken on line 5-5 of Fig. 1; and Fig. 6 is a view of a portion of the valve tube removed from the plate.

Referring to the drawing the numeral 8 indicates the top of a table or other support on which is adapted to rest the gas plate 9 which consists of an annular burner plate 10 provided with concentric recesses 11 in the upper surface thereof and a perforated top plate 12 connected thereto by screws 13. This perforated plate is formed of sheet

metal embossed with concentric ribs or corrugations 14 which coincide with the concentric recesses of the burner plate. The portions 15 of the burner plate on which rests the depressed portions of the perforated top plate are slightly recessed to accommodate an asbestos packing 16 interposed between said burner plate and the perforated plate to form gas tight connections between the concentric recesses 17 formed by said plates. The perforations 18 of the top plate are positioned in concentric lines medially in the top of each rib so that each concentric recess is provided with a line of burner perforations.

The annular burner plate 10 is provided with a projecting tubular extension 19 which extends from the medial portion of the plate to and beyond the periphery of the plate and the opening in the extension intersects the concentric recesses 17 forming openings 20, 21 and 22 to admit gas to said recesses.

A tubular valve 23 having an enlarged conical outer end 24 and an inner closed end 25 is positioned partly within the tubular extension and is adapted to control the supply of gas fed to the burner. The portion of the tubular valve within the extension is provided with valve openings or ports 26, 27, and 28 which are adapted to register with the openings 20, 21 and 22 respectively during certain adjustments of the valve. These openings or ports are of graduated lengths with portions offset and leading the other openings transversely with relation to the tubular valve so that in turning said valve the port 26 will register with the opening 20, a further turning of the valve will move the port 27 into register with the opening 21 and a still further turning of the valve will move the port 28 into register with the opening 22 thus providing means for supplying gas to the inner recess or the inner and the medial recess or all three recesses at the same time to accommodate varying heat requirements. The valve is supplied with gas from a pipe 29 connected to a source of supply and provided with a controlling valve 30 the handle 31 of which extends through an opening 32 provided in the conical end of the tubular valve. A tube 33 extends from the controlling valve and into the tubular valve to form a Bunsen burner of the tubular valve. The plug 34 of the controlling valve is in axial alinement

105

110

with the center of the tubular valve to permit the handle to be freely turned to open and adjust both valves. Part of the air supplied to the burner enters through the 5 end opening of the conical end of the tubular valve and the balance is supplied through the openings 35 which are controlled by the adjustable conical tube 36 which is provided with corresponding air openings.

10 In the use of the gas plate, the controlling valve is attached to a gas supply pipe and if it is desired to heat a small receptacle the valve handle is turned to open the valve and also to turn the tubular valve so that 15 the gas will be supplied only to the inner concentric recess. The gas is now ignited and the small burner provided by the inner recess is well adapted to serve its purpose where but a small flame is desired. The 20 flame is adapted to be adjusted by opening or closing the valve more or less as may be desired to increase or diminish the flame. If it is desired to still further increase the size of the burner the controlling valve is 25 further opened which movement will turn the tubular valve and move the medial port into register with the opening to the medial concentric recess thus furnishing gas to the medial burner which will be ignited by the flame of the inner burner. The gas supply to the medial burner may also be 30 adjusted to increase or diminish the flame in the same manner as the inner burner. If it is now desired to still further augment 35 the flame the valve handle is still further turned to open the valve to full opening and to move the outer port of the tubular valve into register with the opening to the outer concentric recess to supply gas to the outer 40 line of burner openings the gas from which will be ignited by the flame from the medial portion of the burner thus providing a burner which may be increased or diminished in area to form heating units and also 45 providing means whereby the supply of gas to each unit may be regulated by the same controlling valve handle.

From the foregoing description it will be seen that the gas plate is very simple in 50 construction and is very economical in use and the burner may be adjusted to provide the sized flame desired.

What I claim as my invention is:

1. A gas plate, comprising a burner plate 55 provided with a plurality of independent recesses, a top plate connected to said burner plate and provided with a plurality of inde-

pendent sets of burner openings in register with the recesses, a tubular valve connected to the burner plate and provided with ports for controlling the supply of gas to each recess, a valve for controlling the admission of gas to the tubular valve, and a handle for operating both of said valves simultaneously. 60

2. A gas plate, comprising a burner plate provided with a plurality of independent recesses, a top plate connected to said burner plate and provided with a plurality of independent sets of burner openings in register 70 with the recesses, a tubular valve connected to the burner plate and provided with ports positioned to be successively moved into register with the recesses for controlling the supply of gas to each recess, a valve for controlling the supply of gas to the tubular valve, and a handle for operating both of said valves simultaneously. 75

3. A gas plate, comprising a burner plate provided with a plurality of concentric recesses and with a projecting tubular extension, a top plate connected to said burner plate and provided with a plurality of concentric lines of burner openings in register 80 with the concentric recesses, a tubular valve 85 positioned in the tubular extension and provided with independent ports for controlling the admission of gas to each concentric recess, a valve for controlling the admission of gas to the tubular valve, and a handle 90 for operating both valves simultaneously. 90

4. A gas plate, comprising a burner plate provided with a plurality of concentric gas and packing recesses and with a projecting tubular extension, a top plate connected to 95 the burner plate and provided with concentric lines of burner openings and with portions positioned to register with the packing recesses, a packing provided in said packing recesses and interposed between the 100 burner plate and the top plate, a tubular valve positioned in the tubular extension and provided with independent ports for controlling the admission of gas to each concentric recess, a valve for controlling the 105 admission of air to said tubular valve, and a handle for operating both valves simultaneously.

In testimony whereof, I affix my signature, in presence of two witnesses.

HENRY W. SCHULZE.
